CENTER LOCATING DEVICE

George L. Behen, Arvada, Colo., assignor of one-half to Ralph Ashton, Arvada, Colo.

Application April 23, 1943, Serial No. 484,265

1 Claim. (Cl. 33—191)

This invention relates to new and useful improvements in devices for locating the centers of shafts and other structures, the principal object of the present invention being to provide a device of this character which can be utilized in ascertaining the centers of shafts of any cross sectional shape.

Another important object of the invention is to provide a device of this character which is especially adapted for use on stock to be used in turning lathes.

Still another important object of the invention is to provide a center locating device which is not only accurate, but capable of being used quickly and handily with practically no chance of erring.

Other objects and advantages of the invention will become apparent to the reader of the following description.

In the drawings:

Figure 1 represents a top plan view of the instrument.

Figure 2 is a bottom plan view of the instrument.

Figure 3 is an end elevational view of the instrument.

Figure 4 is a side elevational view.

Figure 5 is a fragmentary detailed sectional view taken substantially on the line 5—5 of Figure 1 and showing an offset scribe in use.

Figure 6 is a fragmentary detailed sectional view taken on the line 6—6 of Figure 1.

Figure 7 is a fragmentary detailed sectional view showing a center punch which is used alternately with the scribe shown in Figure 5.

Figure 8 is a fragmentary top plan view showing the guide tongue on one of the complementary angles.

Referring to the drawings wherein like numerals designate like parts, it can be seen that the instrument is composed of a pair of right angle square members 5, 6 each having a pair of arms disposed at a ninety degree angle relative to each other, and the arms of these square members cross as clearly shown in both Figures 1 and 2.

As is shown in Figures 3 and 4, the arms of the square members 5, 6 are slotted longitudinally as at 7, thus defining fingers 8 which interlap at the points of crossing of the arms of the square members. Further, the fingers are longitudinally slotted as at 9 and where the slots 9 of the fingers of the arms of one square member cross the slots 9 of the fingers of the arms of the complementary square member, a bolt 10 is disposed therethrough and also through a washer

11 which bears against a connector bar 12, the bolt 10 passing through a slot 13 which extends longitudinally of the connector bar 12.

Suitable graduations or other micromic reading 14 is provided along one or both arms of the square members.

An elongated beam 15 is fixed to and projects at 45 degrees from the juncture of the arms of the square member 5, across the juncture of the arms of the square member 6 and for some distance therebeyond. This beam 15 has a longitudinal slot 16 therein for receiving a guide tongue 17 which is fixed to and projects beyond the juncture of the arms of square member 6. A set screw 18 having a knurled head is disposed through a cap plate 19 and through the slot 16 and into the tongue 17.

Either an offset scribe 20 can be employed in a holder generally referred to by numeral 21, or a center punch 22 may be employed.

The holder consists of a body 23 having a vertical bore therethrough, this body 23 having a depending boss 24 disposed through both the slots 13 and 16 of the beam 15 and bar 12. The offset scribe 20 has a head 25 and a reduced intermediate portion 26 against which is disposed a set screw 27 which forms part of the holder.

The center punch 22 has a reduced intermediate portion 28 which can be engaged by the aforementioned set screw 27 when this center punch 22 is used instead of the offset scribe 20.

It can now be seen, that when the two square members 5, 6 are forced together or pulled apart, there will be a differentiation of movement of the bar 12 which is regulated by the action of the bolts 10, reacting in response to the action of the square members 5, 6 which, of course, always places the holder 21 in the exact center of the square area defined by the two square members 5, 6.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

A center locating device comprising a pair of right angle square members each having a pair of arms disposed at a 90 degree angle relative to each other, the arms of said square members being slotted longitudinally to define a plurality of fingers for each arm, said fingers interlapping at the points of crossing of the arms and the

fingers of each arm having registered longitudinal elongated slots, a bolt disposed through the slots of the fingers of each pair of crossed arms, a connector bar having a longitudinally elongated slot through which the bolts of both pairs of crossed arms also pass, a guide tongue fixed to and projecting from the juncture of the arms of one of said square members, an elongated beam fixed at one end to the juncture of the arms of the other square member and extending across the first-named juncture of the first-named one

5 of said square members, said beam having a longitudinally elongated slot receiving said guide tongue, a cap plate secured over the beam and to said guide tongue, and a marker including a body disposed on the connector bar and having a boss disposed through the slots of the connector bar and the beam, said body and boss having an axial bore, and a marking element longitudinally adjustable in said bore and projecting from the 10 boss.

GEORGE L. BEHEN.
